UNITED STATES PATENT OFFICE

GRADY W. GARRETT, OF HOUSTON, TEXAS

PIT COVER FOR TOILETS

Application filed March 11, 1927. Serial No. 174,474.

This invention relates to new and useful improvements in a pit cover for toilets.

One object of the invention is to provide a metal slab provided with a tubular riser, or support, for a toilet seat, and cover, and also formed with a tubular vent pipe connection, said slab forming a cover for the toilet pit, as well as the floor of the toilet house or enclosure.

10 The device is specially designed for use in connection with toilets not having connection with a sanitary sewer.

With the above and other objects in view the invention has particular relation to certain novel features of construction, arrangement of parts and use, an example of which is given in this specification and illustrated in the accompanying drawings, wherein:—

Figure 1 shows a perspective view of the 20 slab, as incorporated into a toilet.

Figure 2 shows an end view of the slab.

Figure 3 shows a front view thereof, and

Figure 4 shows a top view thereof.

Referring now more particularly to the drawings, wherein like numerals of reference designate similar parts in each of the figures the numeral 1 designates a suitable toilet house which is erected above the receiving pit 2, which is excavated into the earth. The 25 numeral 3 designates a slab which is preferably formed of metal and which forms the top, or cover of the pit 2 as well as the floor of the house 1. This slab is preferably rectangular in shape and has the marginal depending flanges 4 which penetrate into the earth around the pit and form a tight fit to prevent the escape of fumes from the pit and to form an anchorage for the house 1 as well as to prevent surface water from flowing into 30 the pit. The slab 3 has a suitable circular opening 5, and upstanding from the slab around said opening there is a tubular riser, or seat support 6 which is also formed of metal, and is welded to the slab 3. The top 35 of this riser has an annular outwardly extending flange 7 which, at the rear, is extended forming an anchor 8 to which the toilet seat 9 and the cover 10 thereof may be attached. The anchor 8 is suitably braced 40 by the braces 11 as shown. The slab 3 also

has a similar opening 12 surrounded by the tubular upstanding connection 13, which is welded thereto and the lower end of the fume pipe 14 is telescoped over said connection 13 with its upper end extending up through the roof of the toilet house 1 and through this tube the fumes from the pit 2 may escape.

55 What I claim is:

In a cover for an earth pit, comprising a slab having an opening therein provided with a hopper and seat on its upper side, its lower portion being provided with a substantially continuous depending flange, the margins of which extend beyond the pit completely surrounding the same, and which penetrates the earth, to such a distance to prevent the escape of fumes from the pit, and the entrance of surface water into the pit.

60 In testimony whereof I have signed my name to this specification.

GRADY W. GARRETT.
